UNITED STATES PATENT OFFICE.

LEIGH W. HOSTETTLER, OF TARENTUM, PENNSYLVANIA, ASSIGNOR TO ALLEGHENY STEEL COMPANY, OF BRACKENRIDGE, PENNSYLVANIA, A CORPORATION OF PENNSYLVANIA.

JOURNAL-BOX COVER.

Application filed March 29, 1922. Serial No. 547,707.

To all whom it may concern:

Be it known that I, LEIGH W. HOSTETTLER, a citizen of the United States, and a resident of Tarentum, in the county of Allegheny and the State of Pennsylvania, have made a new and useful Invention in Journal-Box Covers, of which the following is a specification.

The invention relates to journal boxes and more particularly to lids or covers therefor.

Heretofore, in the manufacture of journal box lids, it has been customary to secure the spring which maintains the lid in either open or closed position to the lid by means of rivets.

It has been observed that when springs are secured to the lid or cover members in this manner, the rivet apertures, necessarily formed therein, materially weaken the springs at the very point where the critical bending action occurs. The result has been that when the springs are so attached to the cover members they often became broken, which has necessitated frequent replacements and the consequent expense.

One of the objects of the invention is to provide a journal box lid or cover provided with a spring adapted to resiliently maintain the cover in either open or closed position, that is so attached to the body portion of the cover that the stresses set up therein by the flexing thereof will be distributed through a portion of the spring remote from its point of attachment to the cover rather than localizing adjacent thereto, as heretofore.

Another object of the invention is to provide a journal box cover constructed from pressed metal and having a channel formed therein adapted to extend over the edges of the journal box to provide an effective closure therefor to exclude dust and moisture from the interior thereof.

A further object of the invention is to provide a device, of the character described, that may be quickly and easily constructed from sheet metal and so reinforced as to be very strong and rugged and at the same time of considerably less weight and less expensive to manufacture than the cast metal covers, heretofore, generally employed.

With such objects in view, as well as other advantages which may be incident to

the utilization of the improvements, the invention consists in the parts and combinations thereof hereinafter set forth and claimed, with the understanding that the several necessary elements constituting the same may be varied in proportion and arrangement without departing from the nature and scope of the invention.

In order to render the invention more clearly understood, means are shown in the accompanying drawings for carrying the same into practical effect, without limiting the improvements, in their useful applications, to the particular constructions, which, for the purpose of explanation, are made the subject of illustration.

In the accompanying drawings:

Figure 1 is a front elevational view of a journal box lid constructed in accordance with the invention.

Figure 2 is a vertical sectional view taken on line II—II of Fig. 1 and illustrating the channel portion of the lid in engagement with the edges of a journal box.

Figure 3 is a horizontal sectional view taken on line III—III of Fig. 1 and showing, more in detail, the construction of the spring retaining strap.

Figure 4 is a horizontal sectional view taken on line IV—IV of Fig. 1 and illustrating, more in detail, the construction of the cover.

Referring to the drawings, a portion of a journal box is shown as comprising side walls 1 and top and bottom walls 2. One side of the journal box is open as indicated at 3 to provide for access to the interior thereof. A cover, indicated as a whole at 4, forms a closure for the open side of the journal box and is provided with a plurality of hinge pin eyes 5 adjacent to the upper edge thereof, which are pivotally mounted upon a hinge pin ear 6 formed on the upper wall 1 of the journal box by means of a hinge pin 7.

The eyes 5 of the cover are provided with ear portions 8 which are adapted to be bent over the ends of the pin 7 to prevent the displacement thereof, as shown and described in my co-pending application, Serial No. 425,637.

The edges of the cover 4 are bent, in a direction transverse to the plane of the body portion thereof, to form a flange 9 extend-

ing around the perimeter of the cover. The body portion of the cover 4 is further provided with depressions 10 and with a relatively long narrow depression 11 extending substantially parallel with and adjacent to the lower edge of the cover. The depressions 10 and 11 are adapted to extend partially within the opening 3 of the journal box when the cover is in closed position and co-operate with the flange 9 to form a channel 12 which extends substantially around the cover and which engages the edges of the side and top walls 1 and 2 of the journal box.

15 By this construction, the cover is stiffened and reinforced by the flanges 9 and the depressions 10 and 11 and a very close fit is obtained between the cover and the journal box to effectually exclude dust and moisture from the interior thereof.

A spring 13 is secured to the body portion of the cover, between the depressions 10, by means of a rivet 14 and is adapted to exert yieldable pressure against the eye 6, formed on the journal box, to maintain the cover 4 in an open or closed position in a well known manner. A strap 15, of substantially U-shape, is secured to the cover 4 and straddles the spring 13 at a point slightly above the location where the rivet 14 secures the spring to the cover.

By this construction, the strap 15 forms a fulcrum for the spring 13 to bend upon whereby the critical bending action of the spring 13 occurs at a point adjacent to its fulcrum, rather than at the point where the rivet 14 extends through the spring, which is obviously the weakest part thereof.

40 If desired, a slight amount of play may be permitted between the spring and the strap 15 whereby the bending strain of the spring may be distributed throughout its lower portion.

45 It will be apparent that, by the use of the strap 15, it is only necessary to secure the spring to the cover by means of a single rivet as the strap 15 prevents any tendency of the spring to move in a lateral direction.

50 From the foregoing it will be readily appreciated that a very rugged and relatively inexpensive journal box cover is provided that is of much less weight than the cast iron covers now generally employed and one in which the expense incurred through the replacement of broken springs is materially reduced.

What I claim is:

1. A journal box lid comprising a body portion, a spring attached thereto for co-operation with a journal box to selectively maintain said lid in open and closed positions with respect thereto, and means for relieving said spring of strain adjacent to its point of attachment to said body portion caused by the flexing of said spring.

2. A journal box lid comprising a body portion, a spring attached thereto for co-operation with said journal box to selectively maintain said lid in open and closed positions with respect thereto, and means extending transversely across said spring adapted to relieve the same of strain adjacent to its point of attachment to said body portion, incidental to the flexing of said spring.

75 3. A journal box lid comprising a body portion, a spring attached thereto for co-operation with said journal box to selectively maintain said lid in open and closed positions with respect thereto, and means extending transversely across said spring between its point of attachment to said cover and the free end of said spring to provide a fulcrum upon which said spring is adapted to be bent to relieve said spring, adjacent to its point of attachment, of strain occasioned by the flexing of said spring.

80 4. A journal box lid comprising a body portion, a spring attached thereto for co-operation with said journal box to selectively maintain said lid in open and closed positions with respect thereto, and a strap mounted on said body portion and extending transversely across said spring adapted to provide a bending fulcrum therefor to relieve said spring of strain occasioned by the flexing of said spring.

85 5. A journal box lid comprising a body portion, a spring attached thereto for co-operation with said journal box to selectively maintain said lid in open and closed positions with respect thereto and means for preventing the localization of strain upon said spring adjacent to its points of attachment to said body portion.

90 100 6. A journal box cover comprising a body portion having a channel extending around the same and adjacent to the edges thereof and adapted to engage the edges of a journal box, a spring attached to said body portion and adapted to co-operate with said journal box to resiliently maintain said cover and channel in engagement with the edges thereof to effect a substantially dust and moisture proof closure for said box, and means for preventing the localization of strain in said spring adjacent to its point of attachment to said cover.

110 115 120 125 7. A journal box cover comprising a body portion provided with a flange extending around the periphery thereof, a plurality of depressions adjacent thereto and co-operating therewith to form a continuous channel extending around the outer edge of said body portion adapted to engage the edges of a journal box to effect a substantially dust and moisture proof closure therefor, a spring attached to said cover for co-operation with said journal box to resiliently maintain said channel in engagement with

the edges thereof and a strap secured to said body portion and extending transversely across said spring between its fixed end and the free end thereof and adapted to constitute a fulcrum upon which said spring is adapted to be bent to prevent the localization of strain adjacent to its point of attach-

ment to said cover when said spring is flexed.

In testimony whereof, I have hereunto subscribed my name this 24th day of March, 1922.

LEIGH W. HOSTETTLER.
